Inventor:
Lamar H. Shover
By Young

Attorney:

UNITED STATES PATENT OFFICE.

LAMAR H. SHOVER, OF MILWAUKEE, WISCONSIN.

DISPLAY JAR STAND.

Application filed December 22, 1924. Serial No. 757,463.

To all whom it may concern:

Be it known that I, LAMAR H. SHOVER, a citizen of the United States, and resident of Milwaukee, in the county of Milwaukee, 5 and State of Wisconsin, have invented certain new and useful Improvements in Display Jar Stands; and I do hereby declare that the following is a full, clear, and exact description thereof.

10 This invention relates to display jar stands.

Objects of this invention are to provide a display jar stand in which a plurality of jars are removably mounted and are 15 adapted to revolve about a central axis so as to display any desired jar in an attractive and simple manner, to provide a display stand in which the jars are securely locked in position, and to provide means to permit 20 the ready tipping or rocking of the jars and to thereafter hold such jars in a slanting position to facilitate removing of the contents such as candy thereof during dispensing.

It is to be noted that patrons may rock the 25 jars around in a free manner and it therefore is necessary to provide means for preventing inadvertent tipping of the jars without the sanction of the dispenser or disturbance due to centrifugal force as a result 30 of inadvertent rapid opening of the frame.

A further object is to provide means for permitting tipping of the jars at only one 35 position with reference to the supporting stand. For example, the store keeper may so set the display stand that the jars may be tipped only when they are presented towards him and are remote from the customer.

A further object is to provide latch mechanism which is not opened by centrifugal 40 force, but is held in a more tightly latched condition.

A further object is to provide a display stand which cooperates with a jar having a 45 beaded bottom and avoids any clamping bands or similar members.

A further object is to provide a movable means whereby the number of jars displayed may be varied.

50 Further objects are to provide a simple, attractive and strong display device which may be easily and cheaply manufactured by ordinary machine shop methods.

An embodiment of the invention is shown 55 in the accompanying drawings, in which:—

Figure 1 is a side elevation partly in section of the display stand showing two of the jars in dotted lines.

Figure 2 is a horizontal sectional view showing certain of the parts removed for 60 the sake of clearness and showing one of the jars in section and one in full.

Referring to the drawings, it will be seen that an ornamental base 1 is provided with a centrally positioned tapped hole 2. Within this tapped hole a thread reduced extension 3 of a short spindle or axle 4 is screwed. This spindle or axle is provided with a shoulder or flange 5, and such shoulder or flange 65 clamps a circular disk 6 in position. Preferably the disk and base 1 are locked against relative rotary motion by any suitable means as for example a pin 7, although obviously other means could be employed. This disk is provided with a notch or slot 8 at one portion thereof for a purpose hereinafter to appear.

70 The rotary portions of the device comprise a plurality of channel shaped arms 9 which are securely riveted between upper and lower disks 10 and 11. These disks are apertured and slidably fit the spindle or stub shaft 4.

The outer ends of the arms 9 have riveted thereto short transverse plates 12 which are 85 provided with down turned ears or lugs 13. A plurality of sheet metal jar supports 14 are provided with downturned ears 15, which are positioned outside of the ears 13 and are pivotally secured thereto by means 90 of pintle pins 16 thereby permitting a free rocking motion of the jar supports or plates 14. These jar supports or plates 14 are provided with a pair of upturned inwardly curved retaining lugs or ears 17 at spaced 95 points on their inner sides, as most clearly shown in Figure 2. The outer sides of the plates 14 are each provided with a depressed strap like portion 19 which is separated from the main body of the plates by means of a slit. This strap like portion retains a slide 20 whose outer end is provided with an upwardly extending inwardly curved retaining ear or lug 21 arranged symmetrically with respect to the ears 17. The slide 20 is further provided with a downturned lug 22 and it is to be noted from reference to Figure 100 1 that each of the plates 14 is provided with a similar downturned lug 23. An adjusting or clamping screw 24 passes loosely through

105 110

the lug 22 and is threaded into the lug 23 to provide adjustment for the movable clamping ear or lug 21. It is to be noted that each of the plates 14 is provided with 5 downturned lugs 25 which receive between them the upper end of a latch lever 26, such latch lever being freely pivoted between the lugs. These levers pass through slots 27 formed in the channel arms 9 and are 10 provided with notches 28 adapted to receive a portion of such arms as shown on the left hand side of Figure 1 to thereby lock the plates 14 in horizontal position. These arms are provided with cam-like portions, as 15 shown in Figure 1, to permit their free sliding into locking position when the plates 14 are rocked towards horizontal position. The arms 26 or latch levers are provided with outwardly projecting stop pins 29 which 20 limit the upward motion thereof and thus hold the plates 14 in a predetermined position, as shown in dotted lines on the left hand side of Figure 1.

It will be noted that the latches 26 are 25 prevented from inward swinging throughout the major portion of their path of travel by the plate 6, as such arms will contact with the peripheral portion of the disk or plate 6 before unlatching occurs. However, 30 the notch 8 in the plate provides one point where the latches may be freely rocked inwardly to unlock the plates 14 and permit their outward swinging.

It is to be noted particularly that there is 35 no danger of dropping the jars for the reason that they are securely clamped between the ears or retaining lugs 17 and 21.

If desired an auxiliary standard 30 may be provided and is preferably equipped with 40 a reduced portion 31 adapted to be removably seated in a socket formed in the upper portion of the spindle 4. The upper portion of the standard 30 may carry a sign receiving member or may carry a plurality of arms 45 32 provided with upturned lugs 33 at their ends adapted to retain any suitable article, such as an auxiliary jar or ornamental member.

It will be seen from the description that a 50 very serviceable jar display stand has been provided which permits the free rotation of a plurality of jars about a central point, and which permits the selective tipping of the jars at a predetermined point in their travel, 55 and which will retain the jars in their tipped position and permit the ready removal of the contents as, for instance during dispensing.

It will further be seen that although these 60 highly desirable features of construction and operation are attained that, nevertheless, the

device is extremely simple and rugged and may be cheaply produced.

Although the invention has been described in considerable detail, it is to be understood that the invention may be variously embodied and is, therefore, to be limited only as claimed.

I claim:

1. A jar display stand comprising a base, a spindle carried thereby, a revoluble member pivotally supported by said spindle and having outwardly projecting arms, a tilting plate pivoted to the outer ends of each of said arms, and having a plurality of jar retaining lugs formed thereon, a latch pivotally carried by each of said plates and passing through a slot in a corresponding arm and adapted to temporarily lock the plate in horizontal position and release the same upon movement toward the center of the stand, and means carried by said latch to limit the outwardly swinging motion of such plate.

2. A jar display stand comprising a base, a spindle carried thereby, a revoluble member pivotally supported by said spindle and having outwardly projecting arms, a tilting plate pivotally carried at the outer ends of each of said arms, and having jar retaining means thereon, a latch for locking said plate temporarily in horizontal position, and means carried by said display stand for permitting unlatching of said latches at a predetermined point only.

3. A jar display stand comprising a base, a spindle carried thereby, a revoluble member pivotally supported by said spindle and having outwardly projecting arms, a tilting plate pivoted to the outer end of each of said arms, lugs carried by each of said plates and adapted to engage the base of said jar, one of said lugs being adjustable to clamp said body in place, a latch lever pivoted to each of said plates and having a notch therein, said latch lever passing through a slot formed in the corresponding arm and adapted to receive a portion of such arm in such notch to temporarily lock the corresponding plate in horizontal position, and a disk carried by a stationary portion of said stand and having its periphery arranged in proximity to said latches, said disk having a notch adapted to receive a latch when the revoluble member occupies a predetermined position.

In testimony that I claim the foregoing I have hereunto set my hand at Milwaukee, in the county of Milwaukee and State of Wisconsin.

LAMAR H. SHOVER.
